UNITED STATES PATENT OFFICE.

JUDSON L. THOMSON, OF SYRACUSE, NEW YORK, ASSIGNOR TO THE JUDSON L. THOMSON MANUFACTURING COMPANY, OF SAME PLACE.

PROCESS OF MAKING RIVETS.

SPECIFICATION forming part of Letters Patent No. 423,884, dated March 18, 1890.

Application filed July 1, 1889. Serial No. 316,167. (No model.)

To all whom it may concern:

Be it known that I, JUDSON L. THOMSON, of Syracuse, in the county of Onondaga, in the State of New York, have invented new and useful Improvements in a Process of Making Rivets, of which the following, taken in connection with the accompanying drawings, is a full, clear, and exact description.

My invention relates to the manufacture of sheet-metal rivets of the form described and claimed in my application filed June 21, 1889, Serial No. 315,123; and it consists in an improved method of forming said rivets, which will be readily understood by reference to the description and the accompanying drawings, illustrating said process, and to the claims hereinafter given.

In describing my invention reference is had to the accompanying drawings, illustrating the various steps of my process and forming a part of this specification, in which drawings like letters indicate corresponding parts in all the views.

Figure 1 is an elevation of a rivet-blank consisting of a central enlarged portion and oppositely-arranged arms. Figs. 2 and 3 are respectively plan and elevation of the second step in my process, consisting of holding the central portion of said central enlargement in a certain plane and elevating the surrounding edge of said enlargement, and also the oppositely-arranged arms, into an upright position above said plane. Figs. 4 and 5 are respectively plan and elevation of the third step in my process, consisting in applying pressure from the opposite sides of said upwardly-extending arms or rivet-prongs and approximating them together and lapping the upright edge of the central enlargement of the rivet-blank upon the central portion thereof. Figs. 6 and 7 are respectively plans and elevation of the rivet after the final operation of applying pressure to force said lapped edge of the rivet-head toward the adjacent portion of said head, and thus form the completed rivet; and Figs. 8 and 9 are respectively plan and elevation of a different form of rivet produced by my improved process.

My process is not dependent upon any particular form of mechanism, and as I do not wish the same to be restricted thereto I have

in my present application illustrated no form of mechanism for carrying out my process; but in order that the said process may be readily understood I have illustrated each step 55 thereof by a separate figure.

The rivet-blank A is stamped or cut from sheet metal by any desirable or well-known form and construction of stamping or cutting machine, and said blank consists of the central enlarged portion A', from which the rivet-head is formed, and the oppositely-arranged arms B B, from which the prongs are formed.

The first step of my process consists in holding the center of the enlarged central 65 portion A' of the rivet-blank in a certain plane and then forcing upward the surrounding edge a of the part A' and the oppositely-arranged arms B B. This operation may be effected by any desired form or construction 70 of mechanism—as, for instance, a pair of male and female dies, one of which bears against the center of said portion A' and holds it in the desired plane, and the other of which is provided with a socket of the desired diameter 75 to force said edge and oppositely-arranged arms upward, as illustrated in Figs. 2 and 3. The second step consists in applying pressure to the opposite sides of the upturned rivet-prongs to force them together, as illustrated 80 in Fig. 4. In this case the pressure is not applied to the head a', since it is desirable to form the head of the same diameter as the central depressed portion of the part A' of the rivet-blank. This operation might be 85 effected by oppositely-arranged formers or dies of the exact contour desired, so that when the rivet-blank is subjected to the pressure of said dies or formers the prongs B are sufficiently approximated to form a shank of the 90 desired diameter. I then prefer to subject the top and bottom of the rivet-head a' to the pressure of oppositely-arranged dies or formers in order to force the lapped-over portion a of the enlargement A' upon the adjacent 95 central part in order to effect a neater construction of rivet.

With the form of rivet-prongs b illustrated in the drawings it will be understood that the oppositely-arranged arms B B are tapered 100 when the blank is being stamped or cut, and that said prongs are of such a width as to al-

low a space to intervene between their adjacent edges when the rivet is formed, as illustrated in the drawings.

After constructing the rivet, as described, I prefer to provide the prongs *b* with a cutting-edge *b'*, which may be formed by beveling the same from the inside, but which is, as illustrated, preferably formed by removing the outside portion of the extremities of said prongs, and thus forming a central cutting-edge.

A rivet formed by my improved process has a space intervening between the adjacent edges of the rivet-prongs, which allows the rivet-head to be tightly contacted with the article riveted and prevents the undue compression of said article between the rivet-prongs. It will be also observed that the rivet-prongs are preferably tapering from their extremities toward the head; but it will be understood that I do not limit my process to the forming of any particular construction of rivet-prongs.

At Figs. 8 and 9 I have shown a construction of rivet in which the forming device is so shaped as to force the rivet-prongs into a concave form; but it will be understood that this is no departure from my process. It will also be evident that I do not limit my invention to the time or described order of the steps thereof, and it will be particularly understood that the providing of the rivet-prongs with the cutting-edges may take place at any desired time in the manufacture thereof.

Having thus fully described my invention, what I claim as new, and desire to secure by Letters Patent, is—

1. A process of manufacturing rivets, the same consisting in cutting or stamping from sheet metal a blank composed of a central enlarged portion and oppositely-arranged arms,

subjecting said blank to the action of dies or pressing mechanism for holding the central part of said enlarged portion of the blank in one plane and turning the surrounding edge 45 and oppositely-arranged arms into an upright position above said plane, and then subjecting the opposite sides of said upwardly-extending arms to the action of dies or pressing mechanism for forcing them toward each 50 other, so as to leave a wide space between said arms and form the rivet-shank of less diameter than the rivet-head, substantially as set forth.

2. A process of manufacturing rivets, the same consisting in cutting or stamping from sheet metal a blank composed of a central enlarged portion and oppositely-arranged arms, subjecting said blank to the action of dies or pressing mechanism for holding the 60 central part of said enlarged portion of the blank in one plane and turning the surrounding edge and oppositely-arranged arms into an upright position above said plane, then subjecting the opposite sides of said upwardly-extending arms to the action of dies or pressing mechanism for forcing them toward each other, so as to leave a space between said arms, and finally removing the metal from the extremities of said prongs for forming a cutting-edge thereupon, substantially as set forth.

In testimony whereof I have hereunto signed my name, in the presence of two attesting witnesses, at Syracuse, in the county of 75 Onondaga, in the State of New York, this 15th day of June, 1889.

JUDSON L. THOMSON.
